UNITED STATES PATENT OFFICE.

MORRIS W. BRINKMANN, OF NEW YORK, N. Y.

INDUCTION-COIL.

No. 857,866.

Specification of Letters Patent.

Patented June 25, 1907.

Application filed March 14, 1905. Serial No. 249,978.

To all whom it may concern:

Be it known that I, MORRIS W. BRINKMANN, a citizen of the United States, residing in the borough of Manhattan, city of New York, in the State of New York, have invented certain new and useful Improvements in Induction-Coils, of which the following is a specification, reference being had to the accompanying drawings, forming a part hereof.

10 In induction coils which have a single interrupter the resulting secondary current is determined by the rate of vibration of the interrupter and is necessarily uniform in the sense that a given number of interruptions will occur in a given time. The rate of vibration may be changed by varying the mass, tension, or material of the interrupter, but when once these have been established, the rate will immediately become uniform 15 and the result will be a series of currents of uniform intensity and frequency.

The object of my invention is to provide means whereby a plurality of secondary currents may be produced in the same induction coil, which currents shall be of varying intensity and produced at varying periods of frequency together with suitable means for regulating and controlling the same.

20 The invention consists broadly in providing an induction coil with two or more interrupters and further consists in the new and novel features of construction and combination of parts hereinafter set forth and claimed.

25 Figure 1 is a plan view of an induction coil embodying my invention in its preferred form. Fig. 2 is an end elevation showing one arrangement of the interrupters. Fig. 3 is a side elevation, partly broken away, showing 30 one form of mechanism, for adjusting the interrupters.

In the apparatus embodying my invention which is shown in the accompanying drawings the secondary coil *a* is wound in the usual manner upon a suitable bobbin *b*. This is movable by a screw *c* longitudinally of the primary coil *d*, which is wound in the usual manner about a soft iron core. Preferably the core is provided with a suitable 45 head or enlargement *f*, so as to afford sufficient contact surface for the interrupters. Current is supplied to the primary coil through the binding posts *g* and is controlled by a switch *h*.

50 In the circuit are two or more contact points *i* and interrupters *j*, which are con-

nected to the line circuit in parallel three of each being shown in the drawings. The contact points *i* may be adjusted by means of the thumb-screws *i'* and may be formed of any suitable material and shape to determine the conductivity thereof and thus interpose desired resistance in the circuit. The interrupters *j* may be constructed of such material or may be so formed as to provide resistance in the circuit and comprise two or more strips of ribbons of any desired conducting material, but it is obvious that other forms of interrupters may be used. These ribbons are supported at one end by a suitable standard *k* and at their other ends are provided with suitable holders or clips *l* which are movable in bearings provided by a standard *k'*. Each holder is connected to one end of a lever *m* which is pivoted, as at *n*, to the standard *k'* upon the supporting frame. The free end of each lever is engaged and actuated by a thumb-screw *o*. Preferably said thumb-screws are micrometer screws, in order that the tension of the ribbons can be adjusted accurately. Suitable set-screws *p* are provided in the standard *k'* for holding each of the ribbons in its adjusted position.

The binding posts, being connected with a source of electrical energy, as a battery, and the connections being made, the current will flow through the primary coil thus energizing the core, which will attract each of the ribbons, thus breaking the primary circuit. Since these ribbons are adjusted at different tensions and may be of different materials and mass, the ones having the highest vibratory rates will be the first to return closing the primary circuit. The vibrations will then continue at the vibratory rate of each interrupter as determined by its material, mass and tension. The micrometer screws provide the means for regulating and adjusting the interrupters with relation to each other and to the strength of the current supplied through each contact point so that not only may the rate of vibration of each interrupter be governed, but the periods at which any two or more of the interrupters may make or break the circuit may be governed also, thus securing reinforcement or cessation of the secondary current as desired.

By this construction, it is evident that the maximum effect, that is an induced current having the greatest intensity, will be produced when all the interrupters coincide

either in making or closing the primary circuit, and that this maximum may be produced suddenly or gradually by a series of secondary currents which increase in strength until the maximum is reached. It is likewise evident that the minimum effect is produced when the primary circuit is opened or closed by the interrupter having the greatest electrical resistance and that this effect may also be produced suddenly or gradually. The frequency of the respective periods of maximum and minimum secondary currents is of great importance in producing certain physiological effects particularly upon the muscles, tissues and nerves of the human body. It is obvious also, that since certain results are produced by a given rate of vibration of the interrupters that certain physical conditions or even physiological conditions can be measured and determined in terms of such rate.

Various other objects are within the scope of my invention and I do not intend to limit myself to the attainment only of the objects herein set forth, nor to the precise construction of the apparatus shown, since various

modifications, within the skill of the mechanician can be made in the apparatus, without departing from the spirit of my invention, provided the means set forth in the following claims be employed.

I claim as my invention:

1. An induction coil provided with two or more interrupters operating simultaneously to break the primary circuit.

2. An induction coil provided with two or more interrupters operating simultaneously to break the primary circuit and means for adjusting the tension of each of said interrupters.

3. An induction coil provided with two or more interrupters operating simultaneously to break the primary circuit, each interrupter and corresponding contact point controlling a predetermined current strength.

This specification signed and witnessed this ninth day of March, A. D., 1905.

MORRIS W. BRINKMANN.
